UNITED STATES PATENT OFFICE.

WILLIAM EYNON AND WILLIAM SEAMAN, OF WILMINGTON, DELAWARE.

ROLL FOR ROLLING HORSESHOE-BLANKS.

SPECIFICATION forming part of Letters Patent No. 406,711, dated July 9, 1889.

Application filed December 10, 1888. Serial No. 293,108. (No model.)

To all whom it may concern:

Be it known that we, WILLIAM EYNON and WILLIAM SEAMAN, both citizens of the United States, and residents of Wilmington, New 5 Castle county, Delaware, have invented certain Improvements in Mills for Rolling Horseshoe-Blanks, of which the following is a specification.

The object of our invention is to so construct a mill for rolling horseshoe-blanks that the continuous bar fed into the mill will be rolled into the proper shape for the blanks and severed, so that the blanks issuing from the mill can pass directly to the bending-machine without any further reheating. This 15 object we attain in the manner hereinafter set forth, reference being had to the accompanying drawings, in which—

Figure 1 is a side view, partly in section, of a 20 horseshoe-blank-rolling machine constructed in accordance with our invention. Figs. 2 and 3 are face views, respectively, of the creasing and finishing rolls of the machine; and Fig. 4 is a perspective view illustrating 25 the action of the mill.

In Fig. 1, A represents the frame or housing of the mill, having suitable guides for the boxes *a* of the creasing-rolls *B* and finishing-rolls *D* and for the boxes of lower or carrying rolls *B'* and *D'*, operating in conjunction 30 with said creasing and finishing rolls, respectively, the upper boxes being acted upon by the usual adjusting-screws *b* and the lower boxes being supported by wedge-blocks *d*, while between the two pairs of rolls is a box 35 or trough *F*, which serves to support and guide the bar in its passage from one pair of rolls to the other. The upper or creasing roll *B* has in the present instance two sets of 40 creasing ribs or projections *f f'*, of the usual character, so that it forms two blanks on each rotation of the roll, and between these two sets of creasing-ribs are projecting fins or blades *g*, of such character that they will 45 almost, but not quite, sever the bar between the successive blanks or creased portions.

The rolls *D D'* of the mill provide a pass 50 of the usual form for the finishing of the creased bar; but the rolls *D D'* are so portioned or are so driven in respect to the

rolls *B B'* as to have a slightly greater surface speed than said rolls *B B'*, so that that part of the bar between the two sets of rolls is subjected to a certain amount of draft, the consequence being that the bar is pulled 55 apart at those points where it is weakest—that is to say, where it has been almost severed by the fins or projections *g* upon the creasing-roll—the rolls *D D'* delivering independent and detached blanks, which may 60 pass directly to the bending-machine without further heating.

It will be evident that in carrying out our invention the creasing-roll may be provided with creasing ribs or projections of such character as to produce but one blank on each rotation of the roll, in which case but one fin or projection *g* need be formed on said roll, or the roll may have more than two sets of creasing projections and more than two severing- 70 fins, if desired.

Having thus described our invention, we claim and desire to secure by Letters Patent—

1. The combination, in a mill for rolling horseshoe-blanks, of the creasing-rolls having 75 one or more fins or projections for transversely indenting the bar so as to partially sever the same, and finishing-rolls driven at slightly greater surface speed than the creasing-rolls, so as to impart a slight draft to the bar and 80 tear it apart at the indented portions, all substantially as specified.

2. The combination of the creasing-rolls having one or more indenting-fins for partially severing the bar, the finishing-rolls 85 driven at a greater surface speed than the creasing-rolls, so as to impart draft to the bar and pull it apart at the indentations, and a box or trough for guiding the bar in its passage from the creasing-rolls to the finishing- 90 rolls, all substantially as specified.

In testimony whereof we have signed our names to this specification in the presence of two subscribing witnesses.

WM. EYNON.
WM. SEAMAN.
